Primary Examiner — Amy C Wierenga(74) Attorney, Agent, or Firm — Tyler A. Stevenson;
Anna-lisa L. Gallo(57) CLAIM

We claim the ornamental design for a drain, as shown and described.

DESCRIPTION

FIG. 1 is a top perspective view of a drain showing our new design;

FIG. 2 is a front view thereof;

FIG. 3 is a rear side view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view.

The broken lines illustrate portions of the drain that form no part of the claim.
